HOLDER FOR SUPPORTING MUSIC ON A BAND INSTRUMENT OR SIMILAR ARTICLE

Donald C. Garvey, Evansville, Ind., assignor to Plastic-
Music Company, Evansville, Ind., a corporation of
Indiana

Filed Sept. 1, 1967, Ser. No. 3,479

Term of patent 14 years

(Cl. D56—1)

FIGURE 1 is a front elevational view of a holder for supporting music on a band instrument or similar article, showing my new design;

FIGURE 2 is a rear elevational view;

FIGURE 3 is a side elevational view, the opposite side being substantially a mirror image thereof;

FIGURE 4 is a top plan view;

FIGURE 5 is a bottom plan view;

FIGURE 6 is a front elevational view as it would appear in use with a sheet of music gripped between the front and back gripping members; and

FIGURE 7 is a rear elevational view as it would appear in use with a sheet of music gripped between the front and back gripping members.

The fragmentary broken line showing of a stem for supporting the holder on an instrument and of a representative music sheet are for illustrative purposes only.

I claim:

The ornamental design for a holder for supporting music on a band instrument or similar article, substantially as shown and described.
